Primary Examiner — Sandra S Snapp*Assistant Examiner* — Ieisha N Price(74) *Attorney, Agent, or Firm* — Dunlap Bennett & Ludwig PLLC(57) **CLAIM**

The ornamental design for a lock for ratcheting tie system, as shown and described.

DESCRIPTION

FIG. 1 is a perspective view of a lock for ratcheting tie system;

FIG. 2 is a top plan view thereof;

FIG. 3 is a right side elevation view thereof, the left side elevation view being a mirror image thereof;

FIG. 4 is a bottom plan view thereof;

FIG. 5 is a front elevation view thereof, the rear elevation view being a mirror image thereof; and,

FIG. 6 is section view thereof, taken along line 6-6 in FIG.

4.

The broken lines shown in the drawings depict portions of the lock for ratcheting tie system that form no part of the claimed design.
